(57) **CLAIM**

The ornamental design for a protective cover for a portable electronic device as shown and described.

DESCRIPTION

FIG. 1 is a front perspective view of an embodiment of a portable electronic device cover.

FIG. 2 is a rear perspective view thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

In the drawings, the broken lines represent portions of the article that form no part of the claimed design.
